Primary Examiner — Natasha Vujcic*(74) Attorney, Agent, or Firm* — Justin Lampel(57) **CLAIM**

The ornamental design for a LED lamp holder as shown and described.

DESCRIPTION

FIG. 1 is a top, front and right side perspective view of a LED lamp holder, showing my new design;
 FIG. 2 is a front elevational view thereof;
 FIG. 3 is a rear elevational view thereof;
 FIG. 4 is a left side elevational view thereof;
 FIG. 5 is a right side elevational view thereof;
 FIG. 6 is a top plan view thereof;
 FIG. 7 is a bottom plan view thereof;

FIG. 8 is a top view of the LED lamp holder in a first configuration of use;
 FIG. 9 is a top view of the LED lamp holder in a second configuration of use;

FIG. 10 is a top view of the LED lamp holder in a third configuration of use;
 FIG. 11 is a top view of the LED lamp holder in a fourth configuration of use;

FIG. 12 is a top view of the LED lamp holder in a fifth configuration of use; and,
 FIG. 13 is a top view of the LED lamp holder in a sixth configuration of use.

The broken lines in the drawings depict portions of the LED lamp holder that form no part of the claimed design.
